UNITED STATES PATENT OFFICE

HENRY H. YERK AND WILLIAM J. BAUMBERGER, OF DAVENPORT, IOWA, ASSIGNEES
TO MICRO MACHINE COMPANY, OF BETTENDORF, IOWA, A CORPORATION OF IOWA

GRINDING MACHINE

Application filed April 8, 1927. Serial No. 182,073.

This invention relates to grinding machines and more particularly to portable machines for grinding locomotive wheel crank pins and the like. The machine disclosed in 5 the present invention is similar to that disclosed in our co-pending application Serial No. 130,886, filed Aug. 23, 1926, for improvements in grinding machines, this invention involving improvements in the structure and 10 operating mechanism of the machine.

An object of the invention is to provide a portable grinding machine which may be readily and rigidly disposed in grinding position adjacent a locomotive wheel.

15 A further object of this invention is to provide a grinding machine having improved adjustable elevating means whereby the machine may be readily and accurately positioned with respect to the surface to be 20 ground.

Another object of the invention is to provide a portable grinding machine capable of rapidly grinding relatively large cylindrical surfaces.

25 A further object of this invention is to provide a locomotive crank pin grinding machine of new and novel construction having improved combinations of parts.

Other objects of the invention will be 30 apparent to those skilled in the art from the description of it hereinafter given and the annexed drawings.

In the drawings:

Figure 1 is a perspective view of the grinding machine disposed in cooperative relation 35 with a crank pin and locomotive wheel;

Fig. 1^a is a fragmentary side elevation showing the locomotive wheel crank pin illustrated in Fig. 1;

40 Fig. 2 is another perspective view of the grinding mechanism taken from one side thereof;

Fig. 3 is a front elevation of centering means for use with the machine;

45 Fig. 4 is a longitudinal section on line 4—4 of Fig. 3;

Fig. 5 is a top plan view of the frame of the grinding machine;

50 Fig. 6 is a vertical section on line 6—6 of Fig. 5;

Fig. 7 is a horizontal section on line 7—7 of Fig. 2;

Fig. 8 is a horizontal section taken through the grinding machine carriage on line 8—8 of Fig. 2;

Fig. 9 is a longitudinal section through the upper portion of the grinding machine;

Fig. 10 is a transverse vertical section taken on line 10—10 of Fig. 9;

Fig. 11 is a transverse vertical section 60 taken on line 11—11 of Fig. 9;

Fig. 12 is a horizontal section taken on line 12—12 of Fig. 9;

Fig. 13 is a transverse view partly in section taken on line 13—13 of Fig. 9; and 65

Fig. 14 is a longitudinal section through the grinding wheel spindle, taken on line 14—14 of Fig. 13.

My improved grinding machine comprises generally a frame 1 carrying the wheels 2 and vertically adjustable jacks 3 and 4. Mounted on the frame 1 is a transversely adjustable base 5. In turn, there is mounted on the base 5 a carriage 6 reciprocable longitudinally of said base. Carried by the carriage 6 is a rotatable annular headstock 7 which carries a rotatable grinding wheel spindle 8 and grinding wheel 9. A motor 10 mounted on the carriage 6 supplies power to rotate the headstock 7 and grinding wheel spindle 8 and to reciprocate or oscillate the carriage 6 longitudinally of the base 5. 75

The frame 1 (Figs. 1, 2, 5 and 6) is shown as being substantially triangular in shape, having the sides 11, 12 and 13. To the sides 85 11 and 12 are secured the bearing portions 14 which carry the transversely disposed axle 15 and wheels 2. At the junction of the frame sides 11 and 12 is secured the swiv-able caster 16. A similar caster 17 is shown secured to the front side 13 of the frame substantially midway between the jacks 3. The wheels 2 and casters 16 and 17 are used to transport the grinding machine from one place to another and to dispose the machine 90 adjacent the work to be ground.

Situated adjacent the corners of the frame 1 are the jacks 3 and 4 which may be adjusted vertically individually or simultaneously. The said jacks are movable ver- 95 100

tically in the bearing portions 18 and 19 and are substantially cylindrical in character. The jacks 3 and 4 are shaped along the major portion of their length to form racks 20. 5 Below each rack 20 is a threaded portion 21 arranged to cooperate with a corresponding internally threaded pedestal 22. By means of the threaded portion 21 and pedestals 22, each jack may be independently adjusted vertically. Extending upwardly from the frame 1 are the caps 23, each arranged to enclose the upper portion of a jack.

All the jacks 3 and 4 may be simultaneously moved vertically by suitable means. Thus, 15 adjacent the forward end of the machine (Fig. 5) is a shaft 24 disposed parallel to the axle 15 and supported adjacent its ends by suitable bearing portions 25. The shaft 24 is rotatable and carries pinions 26 arranged 20 to cooperate with the rack portions 20 of the jacks 3. Extending longitudinally of the machine is a shaft 27 rotatably supported on suitable bearing portions 28 and 29 in the frame 1, the shaft 27 having keyed to its forward end a bevel gear 30 arranged to cooperate with a corresponding bevel gear 31 keyed to the shaft 24. Adjacent the rearward end of the shaft 27 is keyed a pinion 32 arranged 25 to cooperate with the rack 20 of the rearward jack 4. Rearwardly of the pinion 32 there is keyed to the shaft 27 a worm wheel 33 cooperatively associated with a transversely disposed worm 34, the said worm being carried by a transverse shaft 35 which 30 may be turned manually by a suitable crank 36 as shown in Fig. 2. By turning the crank 36, therefore, the three jacks 3 and 4 may be raised or lowered simultaneously, whereby to raise or lower the entire grinding mechanism.

40 Referring to Fig. 7, the ends of the shaft 24 are preferably rotatably mounted in suitable bearings, such as the frictionless bearings 37. When the frame 1 has been raised to the desired vertical position, moreover, further 45 vertical movement may be prevented by suitable locking means between the frame and each of the jacks, such, for example, as shown in enlarged form in Fig. 7. Thus, the keyed interiorly threaded sleeves 38 and 39 are disposed in the aperture 40, the set screws 41 extending into the keyways of the sleeves 38 and 39 to prevent rotation thereof. The bolt 42 having the spaced, oppositely threaded portions 43 and 44 extends into the sleeves 50 38 and 39. The bolt 42 is prevented from longitudinal movement by the set screw 45 engaging the bolt 42 between the threaded portions 43 and 44. Upon suitably turning the bolt 42, therefore, the sleeves 38 and 39 55 may be drawn together to engage the jack 3 tightly to prevent vertical movement thereof, and vice versa. Locking means similar to that shown in Fig. 7 for the jacks 3 and jack 4 are indicated at 46 and 47 respectively.

60 55 On the upper surface of the frame 1 are

mounted a plurality of pairs of slideways 49, 50 and 51, and 52, upon which slideways the base 5 rests. Journalized in the portion forming the slideway 51 is a shaft 53 threaded at its inner end and shaped at its outer end to 70 cooperate with a suitable crank 54. The threaded portion 55 of the shaft 53 is arranged to cooperate with the interiorly threaded block 56 carried by and secured to the base 5. By turning the handle 54, therefore, the base 5 may be adjusted transversely of the frame 75 1. The base 5 may be secured in any transverse position of adjustment by bolts 57 and nuts 58, said bolts extending upwardly from the undercut grooves 59 in the slideways 49 and 52 through the bosses 60 of the base 5.

80 At the forward end of the frame 1 is an upwardly extending portion 61 having a top slideway surface 62 and undercut transverse groove 63, and having a front slideway comprising the surfaces 64 and undercut groove 65. An adjustable grinding wheel dressing tool 66 is arranged to cooperate with the groove 63 and thus be adjustable transversely of the slideway surface 62. A member 67 85 (Figs. 5, 6 and 8) having a vertical machined surface 68 is arranged to slide in the groove 65 and along the front slideway surface 64, the said member 67 being adapted to cooperate with a machined surface 69 (Fig. 1) of a locomotive wheel 70 as will be more fully explained hereinafter. Extending transversely of the frame 1 and journaled in the upstanding member 61 is a rod or bar 71, hooks 72 90 adjustable longitudinally of the frame 1 being secured to the ends of said bar, said hooks being arranged to cooperate with the chains 73 for maintaining the grinding machine in rigid position adjacent the locomotive wheel as will more fully appear hereinafter.

95 100 105 The base 5 (Fig. 9) is shown as provided with the transverse end portions 74 and 75 and with the intermediate transverse channel-shaped portion 76. Carried by the end portion 75 and intermediate portion 76 is a longitudinally extending section 77 shaped to form a rack groove 78. Secured to the intermediate transverse section 76 is the block 56 (Figs. 9 and 10) provided with an internally threaded aperture engaging the threaded portion 55 of the shaft 53. The block 56 is shown as provided with the sleeves 79 overlying the threaded portion of the shaft 53.

110 115 120 Disposed in the groove or slideway 78 is the rack 80 which is maintained within the groove 78 by suitable bearing blocks 81 secured to the section 76. Adjacent its rearward end, the rack 80 carries an upwardly extending stub shaft 82 which will be more fully described hereinafter in connection with the longitudinal reciprocation of the carriage 6 from the motor 10.

125 130 When the carriage 6 is to be reciprocated by the motor 10, the rack 80 is locked against

longitudinal movement, but when the carriage 6 is to be reciprocated manually the rack 80 is permitted to move freely in the slideway 78. The rack 80 may be locked 5 against longitudinal movement by suitable means such as shown in Figs. 9 and 11, wherein is shown a bolt 83 extending transversely of the base 5 adjacent the section 76. The bolt 83 has a flanged or hooked end 84 10 arranged to engage one side of the rack 80 and to cause said rack to engage tightly with one side of the slideway 78, as indicated in Fig. 11. The bolt 83 may be held in tightly 15 cooperative relation with the rack 80 by a nut 85 cooperating with the exterior of the base 5.

Means are provided for manually moving the rack 80 longitudinally. Thus, referring particularly to Figs. 9 and 10, a shaft 86 is 20 journaled in the longitudinal base portion 77 and the wall 87 of the base 5. To the shaft 86 adjacent the portion 77 is keyed a pinion 88 engageable with the rack 80. Also keyed on the shaft 86 adjacent the wall 87 is an internal gear 89 engageable with the pinion 90 carried by the shaft 91 which is journaled in the boss 92 and which extends outwardly therebeyond. The shaft 91 is suitably shaped 25 at its outer end to cooperate with manual turning means, such as a crank. By rotating the shaft 91, therefore, the rack 80 can be readily moved longitudinally in the groove 78, and carriage 6 moved longitudinally of the base 5.

Slidable longitudinally on the slideways 93 of the base 5 is the carriage 6. The carriage 6 may preferably engage each slideway 93 on a plurality of surfaces, as indicated in Fig. 10. Suitable adjustable gibs 94 may, of 35 course, be provided to take up wear. At the forward end of the carriage 6 are the bearing portions 95 and 96 arranged to enclose and support the hollow annular rotatable headstock 7. The headstock 7 is preferably provided with a gear 97 for rotation of the headstock. Journaled in the headstock 7 is the spindle housing 98 which may be rotatably 40 adjusted manually or automatically by means to be described. Eccentrically journaled in the spindle housing 98 is the grinding wheel spindle 8 which is preferably mounted in frictionless bearings. The spindle 8 is arranged to be continuously rotated at a relatively high speed during the operation of 45 the machine.

At its forward end, the grinding wheel spindle 8 carries a grinding wheel 9 which is preferably relatively wide and which preferably comprises a plurality of relatively 50 narrow spaced cylindrical wheel portions. The advantages of this form of grinding wheel will appear hereinafter. It will be understood, of course, that relatively narrow grinding wheels may also be employed with 55 my machine without departing from the in-

vention. A suitable grinding wheel guard 99 may partially enclose the periphery of the grinding wheel 9. At its rearward end the spindle 8 carries a driving pulley 100 arranged to receive power from the motor 10. 70

At the rearward end of the carriage, and mounted on the removable top portion 101, is the electric motor 10 arranged to receive electric power from any suitable source of supply. Directly beneath the cover or top 75 101 is a compartment 102 containing power transmission mechanism, and arranged to contain lubricant so that the mechanism therein may be partially or completely submerged in said lubricant.

Mechanism is carried by the carriage 6 for rotating the headstock 7 and simultaneously reciprocating the carriage 6 longitudinally of the base 5, during the rotation of the grinding wheel spindle 8. Thus, referring particularly to Figs. 8 and 9, mounted, preferably in frictionless bearings, in the sleeve 103A, which sleeve is in turn journaled in the bearing portion 103, is the longitudinally extending shaft 104 which carries at its forward end a pulley 105 engaged in driving relation with the pulley 106 on the motor drive shaft 107 by the belt 108. At its rearward end the shaft 104 carries a bevel gear 109 which meshes with the bevel gear 110 disposed intermediate the ends of the stepped collar 111 and keyed thereto. The collar 111 is rotatably mounted on the transverse shaft 112 and is provided with clutch teeth 111A. The shaft 112 which is shown as shouldered at 112A is mounted in frictionless bearings 113 and 113A carried by the non-rotatable sleeves 182 and 183 journaled in the side walls of the carriage 6. The shaft 112 also carries the worm 114. To maintain the gear 110 in engagement with the gear 95 90 100 105 110 115 120 125 130 109 a sleeve 184 is disposed on the shaft 112 intermediate the collar 111 and the adjacent frictionless bearing 113. A bearing washer 185 may be disposed intermediate the collar portion 111 and sleeve 184. Bushings 186 and 187 may be disposed intermediate the shaft 112 and the stepped collar portions 111B and 111C respectively. It will thus be seen that the collar 111 is fixed against longitudinal movement on the shaft 112 by the sleeve 184 and shoulder 112A whereby the gear 110 is maintained in engagement with the gear 109. It will be understood, however, that any suitable means may be employed to retain the gears 109 and 110 in operative relation.

Intermediate the bevel gear 110 and worm 114 is a clutch collar 115 operated by the clutch arm 188, shaft 116 and clutch lever 117 pivoted at 118. The shaft 116 is journaled in the portions 189 and 190. The clutch collar 115 is keyed to and slidable on the shaft 112, the said collar 115 having teeth 115A engageable with the teeth 111A of the gear collar 111 to cause the shaft 112 to rotate with the gear 110. The clutch collar 115 is shown 130

as carrying a sleeve 115B arranged to overlie the teeth 111A and 115A.

Below the transverse shaft 112 and extending longitudinally of the carriage 6 is the shaft 119 journaled at 120 and 121 in frictionless bearings. Directly beneath the worm 114 is the worm wheel 122 keyed to the longitudinal shaft 119, the worm 114 and worm wheel 122 being disposed in driving relation. At the forward end of the shaft 119 is keyed a gear 123 (Figs. 8 and 10) which gear is disposed in cooperative relation to the gear 97 carried by the headstock 7.

Referring particularly to Figs. 8, 9 and 10, it will be seen that the headstock 7 may be rotated from the motor 10, the power being successively transmitted to the pulleys 106, 105, gears 109 and 110, worm 114, worm wheel 122, gear 123, to the gear 97 on the headstock 7. The rotation of the headstock can be stopped or started by manipulation of the clutch collar 115 by the clutch lever 117 as previously described.

The carriage 6 may also be reciprocated longitudinally of the base 5 simultaneously with the rotation of the headstock 7. Thus, rearwardly of the worm wheel 122, the longitudinal shaft 119 (Figs. 8 and 9) carries the worm 124 which cooperates with the horizontally disposed worm wheel 125 keyed to the vertical shaft 126 journaled in the bearing portion 127. Keyed to the lower portion of the vertical shaft 126 below the chamber 102 is the cam member 128 having a cam groove 129 (Figs. 9 and 12). On the previously mentioned stub shaft 82 of the rack 80 is mounted around a bushing 82A a cam roller 130 which said cam roller is arranged to cooperate with said cam groove. It will be understood that the amount of longitudinal movement of the carriage 6 is dependent on the shape and size of the cam 128, and can be varied accordingly.

The cam 128 is preferably shaped to reciprocate the carriage intermittently, with the carriage remaining stationary for a given period at the forward end of the reciprocatory path. In crank pin grinding, the machine is preferably so adjusted that the forward edge of the grinding wheel is disposed adjacent the shoulder of the crank pin portion being ground (Fig. 1^a) when the carriage is in forward position. The carriage preferably remains stationary in forward position while the headstock makes an uneven number of revolutions, such as one and a fraction revolutions. The object of the uneven number of revolutions is to prevent the formation of scallops or patterns on the finished ground surface and to insure uniform even grinding of the surface of the pin adjacent a shoulder thereof. After the said stationary period, the carriage moves to rearward position, forward again, and the above-mentioned operation repeated.

When the rack 80 (Figs. 9 and 11) is free

to move longitudinally, as when the bolt 83 is released, rotation of the cam 128 (Fig. 9) will cause such longitudinal movement of the rack, and the carriage 6 will remain stationary. When, however, the rack 80 is fixed against longitudinal movement, rotation of the cam 128 will cause longitudinal movement or reciprocation of the carriage 6 on the base 5. In causing reciprocation of the carriage 6 on the base 5 by power from the motor 10, it will be seen that the power is successively transmitted through the pulleys 106 and 105, bevel gears 109 and 110, worm 114, worm wheel 122, worm 124, worm wheel 125, and cam 128.

The headstock 7 may also be rotated by manual means. Thus, the transverse shaft 131, journaled in the sleeve 183, may be rotated by a crank handle 132. The inner end of the shaft 131 is provided with a projection 133 arranged to engage with a corresponding detent in the adjacent end of the shaft 112 whereby to rotate said shaft 112. The shaft 131 may be maintained in, or out of, operative engagement with the shaft 112 by suitable means, such as the ball 191 carried in the slot 192 and cooperative with either of the circumferential grooves 193 and 194 in the shaft 131. By rotation of the shaft 131, the headstock 7 may be rotated to a desired position, as indicated in the previous description relating to the rotation of the headstock 7 from the motor 10. From Fig. 8 it will be seen that when the shaft 131 is moved inwardly into engagement with the shaft 112, the collar 195 on the shaft 131 engages the clutch lever 117 to disengage the clutch collar 115 from the collar 111. Conversely, when the lever 117 is operated to engage the clutch collar 115 with the collar 111, the shaft 131 is moved out of operative engagement with the shaft 112. When it is not desired to have the carriage 6 reciprocate simultaneously with the manual rotation of the headstock 7, the bolt 83 may be loosened to relieve the rack 80 from fixed engagement with the base 5.

The grinding wheel spindle 8 may be rotated from the motor 10 at any adjusted position of the spindle housing 98, and moreover, the spindle housing 98 may be manually adjusted or automatically adjusted during the rotation of the spindle 8 and headstock 7. Thus, referring particularly to Figs. 13 and 14, a worm wheel 134 is mounted on the spindle housing 98 adjacent the rearward end thereof. The worm wheel 134 engages with the worm 135 keyed to the shaft 136 journaled in the bracket 137. The shaft 136 may be manually rotated by a crank 138 associated with the suitably shaped outer end of the shaft 136. The spindle housing 98 may, by thus rotating the shaft 136, be rotated manually to the desired position and the grinding wheel spindle 8 disposed at a de-

sired distance from the axis of the headstock 7.

Suitable pulleys are provided whereby the spindle 8 may be continuously rotated at any adjusted position of the spindle housing 98. Thus, a pulley 139 is secured to the forward end of the drive shaft of the motor 10. Mounted on the rearward side of the headstock 7 is a fixed idler pulley 140, and fixed 5 pivotally to the headstock 7 is a crank 141 pivoted on the pin 142, the crank 141 carrying a movable idler pulley 143 at the outer end of one crank arm 144. The other crank arm 145 is adjustably secured to a resilient member or spring 146 secured to the headstock 7. A belt 148 may be suitably associated with the pulleys 100, 139, 140 and 143 as indicated in Fig. 13. The spring 146 is arranged to position the pulley 143 to maintain 10 the belt in tight driving relation at any adjusted position of the spindle housing 98.

Automatic means for rotating the spindle housing 98 to thus automatically feed the grinding wheel 9 to the work to be ground, 25 is shown in Fig. 13. Thus, one of the stops 149 or 150 on the bearing portion 95 may be disposed to trip the arm 151 on every revolution of the headstock to thereby rotate to a desired degree the ratchet 152 mounted 30 on the shaft 153. The rotation of the ratchet 152 causes the worm wheel 154 on the shaft 136 to be rotated by a worm (not shown) mounted on the shaft 153 above the ratchet 152 and beneath the nut 155.

35 Means (Figs. 3, 4 and 9) are provided whereby the axis of the headstock 7 may be disposed in longitudinal alignment with the axis of the crank pin 156 which is shown as having the shouldered cylindrical portions 157, 158, and 159. Thus the spider 160 is shown as having a pair of fixed arms 161 and 162 and an arm 163, the arm 163 being provided with the slidably adjusting means 164 whereby the portion 165 may be brought into 40 or out of engagement with the headstock 7. Each of the arms 161 and 162 and the portion 165 are provided with recesses 166 arranged to engage with the correspondingly shaped surface 167 of the headstock 7. Slidably 45 journaled in the bearing portion 168 is the centering pin 169 having an outwardly tapered portion 170 arranged to engage in a conical centering recess 171 in the crank pin 156. The centering pin 169 is preferably also provided with an adjustable hooked pin 173 arranged to cooperate with a surface, such as 50 the surface 159 of the crank pin to provide positive means for accurately disposing the grinding machine in aligned position with the crank pin axis. Since the crank pin portion 159 is subjected to negligible wear, the hooked pin 173 affords accurate means for aligning the grinding machine. The pin 173 may of course be arranged to cooperate with any of 55 the cylindrical surfaces of the crank pin 156.

In cases where the portion 159 of crank pin is threaded, the centering may be accomplished entirely by the centering pin 169. It will thus be seen that, by means of the centering pin 169 or the scribing pin 173, the grinding machine may be aligned with the axis of the crank pin. 70

A cover plate 197 may be secured to the rear side of the headstock 7 to cover the aperture in the headstock whereby to prevent dust from passing through the headstock and getting into the mechanism rearwardly of the headstock. Annular plates 198 and 199 also may be secured on the forward side of the headstock to the bearing portions 95 and 96, and gear 97, respectively, to exclude dust or the like from the gear 97 and associated parts. 75

My improved grinding machine is particularly advantageous for grinding the crank pins of locomotive wheels such as 70 when said wheels are disposed in upright position as on a track. The wheel shown in Fig. 1 is provided with a machined surface 69 according to the usual construction. 80

In operation the grinding machine is moved 90 adjacent a wheel 70 with the surface 68 of the slideable member 67 directly adjacent the machined surface 69 of the wheel. An ordinary machinist's square may then be employed to determine the perpendicularity of the top surface 62 to the machined surface 69 of the wheel. To dispose the machined surface 69 at right angles to the surface 62, the jacks may be individually raised or lowered by means of the pedestals 22. The jacks 3 and 4 may 100 then be simultaneously raised by the crank 36 sufficiently for the weight of the machine to be carried by the jacks 3 and 4 rather than by the wheels 2 and casters 16. The chains 73 may be disposed around certain spokes to assist in holding the grinding machine in rigid 105 position. The centering spider 160 being in position in the headstock 7, the machine may be raised by means of the crank 36 until the axis of the headstock 7 is in approximate 110 alignment with the axis of the crank pin 156. The pin 169 may then be rotated to determine by means of the hook 173 the exact position of alignment of the headstock 7 with the crank pin 156. The chains 73 may then be 115 tightened by adjusting the nuts 174 to hold the grinding machine rigidly adjacent the wheel 70. The carriage 6 may then be manually reciprocated by turning the shaft 91 to dispose the grinding wheel 9 adjacent the 120 particular surface to be ground, and the nut 85 tightened so that the carriage 6 may be reciprocated from the motor 10 during the grinding operation. The spindle housing 98 may be suitably adjusted by turning the crank 138 125 according to the diameter of the portion of the pin to be ground. The spider 160 is then removed before the grinding operation is commenced. The motor 10 is started and the clutch collar 115 disposed in operative position. 130

tion by moving the clutch lever 117, whereby the grinding wheel spindle 8 is rotated, the headstock 7 simultaneously rotated, and the carriage 6 simultaneously reciprocated longitudinally of the base 5.

It will be noted that the crank pin being ground may extend into the annular headstock 7, thus permitting the grinding of relative long crank pins. Moreover, the headstock 7 may be counterweighted, if desired, as at 200, to counterbalance the weight of the grinding wheel and spindle and housing 98.

It will also be seen that the drive shaft 107 of the motor 10 is in longitudinal alignment with the axis of the headstock 7, whereby smooth uniform rotation of the grinding wheel spindle 8 may be most readily obtained.

As was previously noted, the character of longitudinal movement of the carriage is dependent upon the shape of the cam 128. Variations in the length of reciprocative movement and in the intermittent reciprocation of the carriage may be varied by substituting a different cam 128. It may be noted that the gear ratio of the gears rotating the headstock, and the mechanism reciprocating the headstock are so calculated preferably that the headstock makes one and a fraction revolutions for one complete reciprocation of the carriage. In this manner patterns or scallops in the ground surface are prevented and a smoother finish obtained.

It will thus be seen that we have provided a portable grinding machine of advantageous characteristics for grinding crank pins and the like of locomotive or other wheels.

Our improved machine is readily adjustable and rigid in adjusted position and arranged to grind work with extreme accuracy.

It will moreover be noted that we have provided a grinding wheel which is relatively wide whereby to provide a large grinding surface and whereby but very small reciprocative movement of the carriage is necessary to grind a relatively large cylindrical surface. The grinding wheel may, of course, be integral or may comprise a plurality of relatively thin cylindrical discs which are preferably spaced.

Furthermore, it is to be understood that the particular forms of apparatus shown and described, and the particular procedure set forth, are presented for purposes of explanation and illustration and that various modifications of said apparatus and procedure can be made without departing from our invention as defined in the appended claims.

What we claim is:

1. In a portable grinding machine for grinding locomotive crank pins and the like, in combination, a frame, means associated with said frame to adjust said frame vertically, a base adjustable transversely of said frame, a carriage movable longitudinally of said base, a rotatable annular headstock

mounted on said carriage, a rotatable grinding wheel spindle journaled in said headstock, a motor carried by said carriage, driving means driven by said motor whereby to simultaneously rotate said grinding wheel spindle, rotate said headstock and reciprocate said carriage longitudinally of said base. 70

2. In a portable crank pin grinding machine, in combination, a frame mounted on wheels, means associated with said frame to adjust said frame vertically, a base adjustable on said frame, a carriage mounted on said base and movable longitudinally thereof, a rotatable headstock mounted on said carriage, a spindle housing journaled in said headstock, a grinding wheel spindle eccentrically journaled in said spindle housing, a motor mounted on said carriage, means for manually moving said carriage longitudinally of said base, means for manually rotating said headstock, means for rotating said grinding wheel spindle directly from the shaft of said motor, and means driven from said motor for rotating said headstock and reciprocating said carriage simultaneously with the rotation of said spindle. 90

3. In a portable grinding machine having a base, a carriage movable longitudinally of said base, a rotatable annular headstock mounted on said carriage, and a rotatable grinding wheel spindle carried by said headstock, in combination, a motor, gears driven from said motor, a shaft carrying a worm, a clutch disposed between said aforementioned gears and said worm, a shaft carrying a worm wheel engageable with said aforementioned worm, said shaft carrying another worm, a third shaft carrying a worm wheel engageable with said aforementioned worm and carrying a cam having a cam groove, a rack securable to said base, said rack carrying a roller engageable in said cam groove whereby to reciprocate said carriage longitudinally of said base. 95

4. In a portable grinding machine, in combination, a frame, a base adjustable transversely of said frame, a carriage movable longitudinally of said base, said base being shaped to form a longitudinally extending groove, a rack longitudinally movable in said groove, means for securing said rack against longitudinal movement, a cam roller carried by said rack, a hollow cam carried by said carriage, said roller engaging in cooperative relation with said cam, manually operable means for longitudinally moving said rack when said rack is freely movable whereby to move said carriage to a desired position, and means for rotating said cam when said rack is secured against longitudinal movement, whereby to reciprocate said carriage longitudinally of said base. 110

5. In a portable grinding machine, in combination, a base, a carriage movable longitudinally of said base, a shaft carried by said

carriage, a gear arranged to transmit power to said shaft, a clutch interposed between said gear and said shaft to operatively connect or disconnect said gear with or from said shaft, 5 headstock rotating mechanism operable by rotation of said shaft, means arranged to engage said shaft whereby said shaft, and consequently said headstock, may be manually rotated, and means to automatically operate said clutch to disconnect said gear from said shaft when said manual shaft rotating means is brought into operative relation with said shaft.

6. In a portable grinding machine for 15 grinding locomotive wheel crank pins and the like, in combination, a supporting frame arranged to be disposed on a floor adjacent the work, a carriage reciprocable longitudinally of said frame and the surface to be ground, a 20 rotatable headstock carried by said carriage, a grinding wheel carried by said headstock, said headstock being revoluble exteriorly of the work to grind an external cylindrical surface thereon, and adjustable means carried by 25 said frame for raising and lowering said carriage to dispose said headstock in desired position relative to the work to be ground.

7. In a portable grinding machine for 30 grinding a horizontal crank pin on an up- standing locomotive wheel having a vertical machined surface, in combination, a supporting frame arranged to be disposed on a floor adjacent said locomotive wheel, said frame having a machined surface arranged to abut said 35 locomotive wheel machined surface, a carriage carried by said frame, a rotatable grinding wheel spindle carried by said carriage revolu- 40 ble exteriorly of said crank pin to grind an external cylindrical surface thereon, means carried by said frame for adjusting portions of 45 said frame vertically to dispose said grinding wheel spindle with the axis of orbital movement thereof in a horizontal plane and to dispose said frame machined surface in vertical 50 position whereby said frame machined surface may abut said locomotive wheel machined surface, and means carried by said grinding machine to adjust said carriage vertically and laterally whereby said grinding 55 wheel spindle may be disposed with the axis of orbital movement thereof in exact longitudinal alignment with the axis of the surface to be ground on said crank pin and whereby said crank pin may be provided with a cylindrical ground surface disposed in exact horizontal position.

8. In a portable grinding machine for 60 grinding locomotive wheel crank pins and the like, in combination, a supporting frame arranged to be disposed on a floor adjacent the work, a carriage carried by said frame, a rotatable headstock carried by said carriage, a 65 rotatable grinding wheel carried by said headstock and revoluble exteriorly of the work to grind an external cylindrical surface

thereon, means carried by said grinding machine for adjusting the position thereof relative to said work, and means carried by said headstock arranged to extend forwardly thereof toward said work to cooperate with said work whereby said machine may be readily disposed with the axis of orbital movement of said grinding wheel spindle in longitudinal alignment with the axis of the cylindrical surface to be ground in said work.

In testimony whereof we affix our signatures.

WILLIAM J. BAUMBERGER.
